Application July 30, 1932, Serial No. 627,068
In Germany August 5, 1931

7 Claims. (Cl. 179—18)

The invention relates to improvements in telephone systems and has for one of its objects the elimination of the contacts (off-normal contacts, rotary off-normal contacts) which are actuated by the switch when it operates and which continue to be actuated until the switch is restored to normal.

This, according to one feature of the invention, is achieved by maintaining a relay, actuated over one of the wipers of the switch when the latter leaves its normal position, energized independent of the energizing circuit extending over the switch wiper, so that it continues to function until the switch is restored to normal.

15 The invention is also concerned with a telephone system provided with switches which operate as call finders for one traffic direction and final selectors for the other traffic direction, and a further object of the invention is to 20 simplify in a simple and reliable manner the setting of this type of switch which is provided with a plurality of contact groups, this being achieved by providing auxiliary devices which mark the required contact groups.

25 The invention will be better understood from the following description of one method of carrying it into effect which should be taken in conjunction with the accompanying drawings.

The embodiment illustrated represents a 30 private branch exchange system in which the subscriber is able to set up internal connections over the connecting devices AS, LW1 and LW2 and may obtain a connection with an exchange line AL after the final selector LW2 has been 35 set to a definite contact.

Setting up a connection within the private branch exchange

When the subscriber T with the object of setting up a local connection lifts his receiver, relay 40 T is energized over; earth, contact 1t, subscriber T, contact 2t, resistance W, relay T, battery, earth. Relay T is of the two step type and actuates contacts 3t and 4t only in the first stage.

45 The calling subscriber is marked by contact 3t at the c-wiper of the call finder AS while contact 4t closes the following circuit for relay V: earth, contacts 4t, 6a, winding I of relay V, b-wiper of the stepping switch WR in position O, contacts 7w1, 8w2, 13w2, rotary magnet D1, battery, earth. Relay V only is energized in this circuit while the rotary magnet D1 in known manner is prevented from operating. Relay V closes a circuit for the rotary magnet D as follows: earth, contacts 15c, 16a1, 17v, 18d, rotary

magnet D, battery, earth. The rotary magnet D operates and advances the call finder AS one step. Contact 18d is opened simultaneously with the energization of the rotary magnet D and cuts off the circuit for said rotary magnet. This 60 restores contact 18d to normal so that the circuit for the rotary magnet D is re-established. The rotary magnet thus with the aid of its contact 18d operates as a self-interrupter until the following circuit has been completed: earth, battery, relay T, contact 3t, c-wiper set on the calling subscriber's contact, relay A1, contacts 19wr, 20v, earth. Relay A1 is energized in this circuit and at contact 16a1 cuts off the circuit for the rotary magnet D and at contact 21a1 70 closes the following circuit for relay A: earth, contacts 22c, 21a1, 12w2, 11w1, winding II of relay A, battery, earth. Relay A is thus energized and at contact 23a closes a circuit for relay C as follows: earth, contacts 23a, 24u, relay C, battery, earth. Relay C is energized and at contact 22c opens the circuit for relay A over winding II. Relay A, however, does not yet relapse due to the fact that over contacts 25c and 26c the following locking circuit for it has been 80 closed: earth, battery, winding II of relay A, contacts 25c, 27p1, a-wiper of the call finder AS over the calling subscriber's line loop, b-wiper of the call finder AS, contacts 28p1, 26c, winding I of relay A, earth, which circuit, after relay A1 has been released due to short-circuit at 85 contact 29c, causes relay T to be energized in its second stage and consequently cuts off the ringing circuit by opening its contacts 1t and 2t. The opening of contact 5t breaks the circuit for relay V over winding I. Relay V, however, does not relapse due to the following locking circuit: earth, contact 30c, winding II of relay V, contact 31v, c-wiper of the stepping switch WR in position O, battery, earth. Relay V closes the 90 following circuit for relay E: earth, contact 32v, relay E, battery, earth.

Two parallel connected rotary final selectors are used in the present embodiment and each 100 switch is provided with a plurality of contact groups. Both the final selectors LW1 and LW2 are provided with five contact groups each comprising 10 line connected contacts with the result that 100 lines are accessible over the two final selectors LW1 and LW2.

If, therefore, the called subscriber is accessible over a contact of the final selector LW1 and connected for example to contact 45 of said final selector, the stepping switch WR has 110 to be set to contact 5. The calling subscriber

consequently must transmit five impulses first, which, in known manner, cause relay A to be de-energized a number of times corresponding to the number of line loop breakings and the 5 driving magnet of the stepping switch WR to be operated accordingly over: earth, contacts 30c, 33b, 34a driving magnet WR, battery, earth. When the c-wiper of the stepping switch WR leaves its normal position, the circuit extending over winding II of relay V is cut off. Relay V, however, remains energized during the impulse series in the following circuit: earth, contact 30c, winding II of relay V, contact 35a, battery, earth. Relay V relapses at the end of 10 the impulse series and opens the circuit for relay E at contact 32v. When relay E releases, the following circuit for the rotary magnet D1 of the final selector LW1 is closed: earth, battery, rotary magnet D1, contacts 13w2, 8w2, 7w1, b-wiper of the stepping switch WR in position 1-10, contacts 36p, 37a1, 38e, 39d1, 40d2, 41b, earth. The rotary magnet is energized and causes the final selector to advance one step. The following circuit is then closed for relay 15 W1 over the e-wiper of the final selector LW1: earth, battery, resistance W1, e-wiper of the final selector LW1 set to contact 1, winding I of relay W1, earth. Relay W1 is energized and closes its own locking circuit: earth, battery, resistance W1, contact 42w1, winding I of relay W1, earth. Relay W1, consequently, is energized after the first actuation of the final selector LW1 and throws over its contacts which are only restored to normal when the final selector LW1 reaches its original position in a manner to be explained in a later paragraph. By 20 means of the contacts of relay W1 therefore, the contacts may be dispensed with which are directly influenced by the actuation of the switch, that is to say, the so-called off normal or rotary off-normal contacts.

Relay W1 opens contact 7w1 and closes 9w1 so that the circuit for the rotary magnet D1 is influenced independent of the b-wiper of the stepping switch WR. Contact 39d1 is opened on 25 the first energization of the rotary magnet D1 and this breaks the circuit for said magnet. Contact 39d1 is then re-closed which causes the circuit for the rotary magnet D1 to be re-established. The rotary magnet D1 with the aid of contact 39d1 thus operates as a self-interrupter until the e-wiper of the final selector LW1 has reached the contact marked by the a-wiper of the stepping switch WR. Due to the a-wiper 30 of the stepping switch WR being set to contact 5 by the first impulse series, the switch wipers of the final selector are continually advanced until the e-wiper of the final selector LW1 has reached contact 40 when the following circuit for relay B is closed: earth, contact 30c, winding II of relay B, contact 43v, a-wiper of the stepping switch WR set to contact 5, e-wiper of the final selector LW1 set to contact 40, resistance W1, battery, earth. Relay B at contact 35 41b opens the circuit for the rotary magnet D1. Furthermore, contact 44b causes a locking circuit to be completed for relay B as follows: earth, contacts 30c, 44b, winding I of relay B, battery, earth. The energization of relay B causes a circuit for relay V to be closed over: earth, contact 30c, winding II of relay V, contact 45b, a-wiper of the stepping switch WR set to contact 5, e-wiper of the final selector LW1 set to contact 40, resistance W1, battery, earth.

Relay V is energized and at contact 43v cuts off the circuit over winding II of relay B. Relay E also is re-energized over: earth, contact 32v, relay E, battery, earth.

The calling subscriber now has to transmit an additional five impulses since he can only reach the required subscriber over the 45th contact of the final selector LW1. These impulses cause the rotary magnet D1 of the final selector LW1 to be actuated over: earth, contacts 30c, 46b, 47a, 48e, 37a1, 36p, 9w1, 8w2, 13w2, rotary magnet D1, battery, earth due to relay A closing its contact 47a in accordance with the occurring line loop breakings. When the e-wiper of the final selector LW1 leaves contact 40, the circuit for relay V is cut off but this relay still remains energized during the operation of relay A over: earth, contact 30c, winding II of relay V, contact 35a, battery, earth. Relay V does not relapse until the end of the impulse series, when, at contact 32v it opens the circuit for relay E. Relay E, however, remains energized a short period after the release of relay V with the result that if the called subscriber's station is idle the following circuit in which relay P is 100 energized is closed: earth, contacts 49b, 50v, 51e, windings II and I of relay F, winding I of relay P1, c-wiper of the final selector LW1 set to the called subscriber's contact, the called subscriber relay T, battery, earth. Relay P at contact 52p short-circuits winding II and maintains the test circuit independent of contact 51e. The closing of contacts 53p and 54p causes the lines to be switched through in the final selector.

Ringing current is applied to the called subscriber from the ringing current source of supply over: winding II of relay U, contacts 55u, 53p, a-wiper of the final selector LW1 set to the called subscriber's contact, the called subscriber's station, back over the b-wiper of the final selector LW1, contacts 54p, 28p1, 26c, winding I of relay A, earth. When the called subscriber answers, relay U is energized in known manner in the ringing pause and by opening contact 24u and closing contact 56u is placed in the following locking circuit: earth, contacts 23a, 56u, winding I of relay U, battery, earth. Relay C, after subsequent testing and energization of relay P is maintained energized over contact 57p independent of contact 24u. The ringing current is cut off by the opening of contact 55u whereas the a-lead of the final selector is switched through due to the closing of contact 53u. The speaking connection between the calling and called subscribers is then completed.

Relay A is de-energized when, at the end of the call, the two subscribers replace their receivers. This relay thus relapses and at contact 23a opens the circuit for relay C which in turn opens contact 30c and closes 60c thus transmitting impulses from the relay interrupter RU to the driving magnet WR of the stepping switch WR over: earth, contact 60c, e-wiper of the stepping switch WR set to contact segment 1-10, driving magnet WR, battery, earth, which impulses cause the stepping switch WR to be restored to normal. The opening of contact 30c cuts off the circuit for relay B over winding I. This relay releases and restores its contacts to their original positions whereupon contact 49b breaks the circuit for relay P which then also restores its contacts to normal so that a circuit for the rotary magnet D1 is closed over: earth, battery, rotary magnet D1, contacts 13w2, 8w2, 9w1, 36p, 37a1, 38e, 39d1, 40d2, 41b. The rotary 150

magnet D1 by means of its contact 39d1 operates as a self-interrupter and causes the switch wipers of the final selector LW1 to advance until the e-wiper of said final selector has reached its normal position and consequently connected up a differential winding of relay W1 over: earth, battery, resistance W1, e-wiper in normal position, contact 61w1, winding II of relay W1, earth, with the result that the contacts of relay W1 are restored to normal, which cuts off the circuit for the rotary magnet D1 at contact 9w1. All the various switching means in the system are then restored to their original positions.

If the required subscriber should be connected to, for example, contact 25 of the final selector LW2, the calling subscriber has first to send out 8 impulses and thus cause the stepping switch WR to be set to contact 8. The switching operations as far as the setting of the stepping switch WR are concerned are the same as those already described. When the stepping switch WR however, during its advance to contact 8 reaches contact 6, relay W2 will be energized over: earth, battery, resistance W1, d-wiper of the stepping switch WR set to contact 6, winding I of relay W2, earth. Relay W2 closes its contact 59w2 thus completing its own locking circuit as follows: earth, resistance W1, contact 59w2, winding I of relay W2, earth. Relay W2 opens contacts 8w2 and 13w2 and closes contacts 10w2 and 14w2. Firstly a switching over from the rotary magnet D1 to D2 is then carried out and secondly the circuit for the rotary magnet D2 is closed independent of the b-wiper of the stepping switch WR.

After the stepping switch WR has finally been set to contact 8, relays V and E relapse in the manner described previously and the rotary magnet D2 is connected up over: earth, battery, rotary magnet D2, contacts 14w2, 10w2, 36p, 37a1, 38e, 39d1, 40d2, 41b, earth and advances the switch wipers of the final selector LW2 one step. When the rotary magnet D2 operates, however, contact 40d2 is opened and cuts off the circuit for this rotary magnet so that it is de-energized and restores contact 40d2 to normal which then re-energizes the rotary magnet D2. The rotary magnet D2 therefore in the present case, with the aid of contact 40d2, operates as a self-interrupter. When the final selector LW2 has been set to contact 70, a circuit for relay B is completed in the manner previously described. Relay B at contact 41b opens the circuit for the rotary magnet. Additional impulses transmitted by the calling subscriber cause the rotary magnet D2 to operate over: earth, contacts 30c, 46b, 47a, 48e, 37a1, 36p, 10w2, 14w2, rotary magnet D2, battery, earth. The final selector is advanced an additional five steps with the result that the switch wipers of the final selector LW2 are set to the required contact which is connected to the 25th contact. The further switching operations are exactly the same as those previously described in conjunction with the setting of the final selector LW1.

The release of the final selector LW2 at the end of the call is carried out in the following manner: Relay A is de-energized when the two subscribers replace their respective receivers. This relay then cuts off the circuits for relays C and U at its contact 23a. Due to the release of relay C the driving magnet WR of the stepping switch WR receives impulses over: earth, contact 60c, relay interrupter RU, e-wiper of the stepping switch WR set to contact

segment 1—10, driving magnet WR, battery, earth. The driving magnet is caused to operate until the stepping switch has been restored to normal when the above-mentioned circuit for the driving magnet is cut off. The release of relay C with the consequent opening of contact 30c breaks the locking circuit for relay B. The relapse of relay B causes the circuit for relay P to be cut off at contact 49b with the result that the contacts of relay P are restored to normal. The following circuit for the rotary magnet D2 is then closed: earth, battery, rotary magnet D2, contacts 14w2, 10w2, 36p, 37a1, 38e, 39d1, 40d2, 41b, earth. The rotary magnet with the aid of its contact 40d2 operates as a self interrupter and advances the switch wipers of the final selector LW2 until it reaches its normal position in which a differential winding of relay W2 is connected up over: earth, battery, resistance W1, e-wiper in normal position (contact 50), contact 62w2, contact 13oc, winding II relay W2, earth which causes the contacts of relay W2 to be restored to normal so that the circuit for the rotary magnet is cut off at contact 10w2. The final selectors LW1 and LW2, therefore, may only be seized for a fresh call after contact 8w2 has been restored to normal due to the fact that they are accessible over said contact 8w2 only.

Relays W1 and W2 thus, by means of their contacts replace the ordinarily provided off normal contacts operated as soon as the switches LW1 or LW2 advance out of their original position. Contacts 9w1 and 10w2 consequently make it possible to operate the rotary magnets D1 or D2 independent of the stepping switch WR. Contacts 7w1 and 8w2, as long as the final selectors LW1 or LW2 have not reached their normal position, prevent a fresh seizure of said final selectors. Furthermore, relay W2 determines which rotary magnet is to be operated according to the transmission of the first impulse series.

Setting up an exchange connection

For the setting up of an exchange connection from a private branch exchange the final selector LW2 has to be set to contact 01, that is to say, the calling subscriber must first dial the digit 0 and thus cause the stepping switch WR to be advanced in the manner previously described. The transmission of 10 impulses causes the stepping switch WR to be set to contact 10 and the final selector LW2 is caused to advance until its e-wiper has reached contact 90, in other words, the switch wipers of the final selector LW2 must pass over four groups comprising 10 contacts each before they reach contact 90. The switching operations performed for the setting of the call finder and the final selector LW2 are exactly the same as those described in conjunction with the setting up of an internal connection. When the final selector LW2 has been set to contact 01, the following circuit is closed: earth, contacts 49b, 50v, 51e, winding II and I of relay P, winding I of relay P1, c-wiper of the final selector LW2 set to contact 01, relay An, battery, earth. Relay An only is energized in this circuit. Relay An closes its contacts 63an and 64an. The following test circuit is prepared at contact 63an: d-wiper of the call finder AS and d-wiper of the switch AW. Due to the actuation of contact 64an relay R is energized over: earth, contacts 64an, 65c1, 66b1, winding I of relay R, battery, earth. Relay R

- closes its contact 67r which causes the rotary magnet D3 of the switch AW to be energized over: earth, relay interrupter RU1, contact 68c1, d-wiper of the stepping switch WR1 set to contact 0, contact 67r, rotary magnet D3, battery, earth. The rotary magnet D3 continues to advance until the d-wiper has reached the contact marked over the d-wiper of the final selector LW2 and the d-wiper of the call finder AS at contact *d* of the switch AW whereupon the following test circuit is closed: earth, battery, resistance W2, contact 63an, d-wiper of the final selector LW2 in position 01, winding II of relay P1, d-wiper set to the calling subscriber's contact, d-wiper of the switch AW, contact 68r, winding III of relay C1, winding II of relay R, earth. Relay C1 is first energized in this circuit and at contact 68c1 cuts off the circuit for the rotary magnet D3. The opening of contact 65c1 prevents another subscriber from seizing the exchange line AL.
- In addition, relay P1 is energized over the d-wiper of the switch AW and the d-wiper of the call finder AS. Relay P1 closes its contact 69p1, thus causing relay U to be energized over: earth, contacts 23a, 69p1, winding I of relay U, battery, earth. Relay U at contact 24u cuts off the circuit for relay C whereupon the stepping switch WR and the final selector LW2 are restored to normal in the manner previously described. All the switching means associated with the call finder AS and the final selector LW2 are then restored to normal. When relay C consequently releases and opens contact 29c, a locking circuit for relays C1 and T is closed over: earth, contact 70c1, winding I of relay C1, the c-wiper set to the calling subscriber's contact, line 71, relay T, battery, earth.
- The switching-through operation is carried out by relay C1 at contact 72c1 and 73c1 so that relay S can be energized over: earth, battery, contact 74h, windings III and I of relay S, contact 72c1, a-wiper set to the calling subscriber's contact, line 75 over the subscriber's station T, line 76, b-wiper of the switch AW set to the calling subscriber's contact, contact 73c1, winding II of relay S, earth. Relay S causes relay B1 to operate over: earth, contacts 77S, 78A, relay B1, resistance W3, battery, earth.
- Relay B1 closes contact 80b1 which closes the following circuit for relay V1: earth, contacts 81c1, 80b1, relay V1, battery, earth.
- The subscriber is now connected to the exchange line and in a position to cause the setting of the appropriate devices in the exchange in any known manner. When, at the end of the conversation, the subscriber T replaces his receiver, relay S relapses. It then opens contact 77s and closes 79s, causing relay B1 to be short-circuited. Prior to relay B1 restoring its contacts to normal, however, winding I of relay C1 is short-circuited over: earth, contacts 82v1, 83b1, 84s. Relay C1 releases and restores its contacts to normal. When relay B1 now relapses, the circuit for relay V1 will be cut off at contact 80b1. Due to the release of relay C1 and subsequent opening of contact 70c1, the calling subscriber's relay T also is de-energized so that it restores its contacts to normal. All the switching means actuated for this connection have then been restored to their original positions.
- Setting up an incoming exchange connection*
- As will be appreciated from the aforesaid the switch AW in outgoing connections operates as a call finder. If, on the other hand an incoming call arrives over the exchange line AL, the operator receiving the exchange call causes the switch AW to be set by means of impulses in the following manner: The ringing current from the exchange energizes relay A2 in known manner so that a circuit for the signal lamp L is completed over: earth, battery, contact 85a2, lamp L, earth. At the same time the following circuit is closed for relay H: earth, battery, contacts 85a2, 86A, 87b1, relay H, earth. Relay H closes its contact 88h and is thus placed in the following locking circuit: earth, battery contacts 89s, 88h, relay H, earth. The operator then throws over her enquiry key the contacts of which are all denoted by A so that when contacts 92A and 93A have been closed, the operator's set is connected to the exchange line AL. The throwing over of the enquiry key causes contact 78A to open and 94A to close causing the following energizing circuit to be completed for relay B1: earth, contact 94A, relay B1, resistance W3, battery, earth. Relay B1 closes its contact 95b1 and is thus placed in a locking circuit independent of the enquiry key. The opening of contact 66b1, in addition, prevents the exchange line from being seized by another substation subscriber.
- The operator now enquires the number required by the calling exchange subscriber and after having received it throws over a key, the contacts of which are all denoted by R. This causes relay V2 to be energized over: earth, contact 96R, c-wiper of the stepping switch WR1 in zero position, winding I of relay V2, battery, earth. Relay V2 at contact 97v2 prepares a circuit for relay E1.
- It will now be assumed that the required exchange subscriber is connected to for example contact 45 of the switch AW. The operator then has to transmit five impulses and thus cause the switch WR1 to be set to the fifth contact in the following way. The operator's impulse sender causes contact 88ik to be actuated so that the driving magnet WR1 operates over winding I in the following circuit: earth, battery, winding I of the driving magnet WR1 of the stepping switch WR1, contacts 99f, 100R, 88ik, earth. The driving magnet WR1 receives five impulses and consequently sets its wipers to contact 5. As soon as the stepping switch WR1 leaves its normal position, relay E1 is energized over: earth, contact 96R, c-wiper of the stepping switch WR set to the contact segment 1-10, contact 97v2, relay E1, battery, earth due to the fact that after the stepping switch WR1 has left its zero position relay V2 also remains energized over: earth, contact 96R, c-wiper of the stepping switch WR1 set to the contact segment 1-10 while impulses are applied to the driving magnet WR1 and contact 101wr1 consequently is closed in accordance with its actuation. Due to its slow action relay V2 does not follow the interruptions set up by contact 101wr1. Relay V2 relapses at the end of the first impulse series and consequently causes relay E1 also to release due to the opening of contact 97v2. During the actuation of contact 101wr1 and the energization of relay E1, relay E1 and, over contact 102e1 the rotary magnet D3 of the switch AW are disposed in parallel with winding I of relay V2. The rotary magnet D3 cannot operate when placed in parallel with relays V2 and E1. When, however, relay E1 releases, contact 102e1 is opened and 103e closed.

This completes the following circuit for the rotary magnet D3 of the switch AW: earth, relay interrupter RU1, contact 68c1, *d*-wiper of the stepping switch WR1 set to contact segment 1—10, contacts 104R, 105f, 103e1, rotary magnet D3, battery, earth. The rotary magnet now receives impulses until the *e*-wiper of the exchange switch reaches contact 40 whereupon the following circuit is established: earth, battery, resistance W4, *e*-wiper of the switch AW set to contact 40, *a*-wiper of the stepping switch WR1 set to contact 5, contact 106v2 winding I of relay F, *b*-wiper of the stepping switch WR1 set to contact segment 1—10, contact 107R, earth. When the *e*-wiper of the switch AW leaves its normal position and reaches contact 1, relay W3 is energized over: earth, battery, resistance W4, *e*-wiper of the switch AW set to position 1 and 2, winding I of relay W3, earth. Relay W3 closes its contact 108w3, thus completing the following locking circuit in which it is placed: earth, battery, resistance W4, contact 108w3, winding I of relay W3, earth. Relay W3 in this manner replaces the off-normal or rotary off-normal contacts of a switch since this relay, as explained above, functions on the first rotary step of the switch AW and by means of a differential winding does not restore its contacts to normal until the said switch reaches its original position. A signal lamp L1 is connected up parallel to contact 106v2 and relay F and this lamp indicates to the operator when she may commence to transmit the second impulse series. Relay F, however, first opens contact 105f which breaks the circuit for the rotary magnet D3. Relay F remains energized over: earth, contacts 109w3, 110f, winding II of relay F, battery, earth. Relay R causes relay V2 to respond over winding II since the following circuit is completed: earth, battery, resistance W4, *e*-wiper of the switch AW set to contact 40, *a*-wiper of the stepping switch WR1 in position 5, contact 111f, winding II of relay V2, *b*-wiper of the stepping switch WR1 set to position 1—10, contact 107R, earth. Relay V2 is energized and at contact 106v2 cuts off the energizing circuit for relay F over winding I. Relay V2 causes relay E1 to be energized over contact 97v2, with the result that the rotary magnet D3 is now operated by the additional impulses which the operator transmits over the impulse contact 88ik over: earth, contacts 88ik, 100R, 112f, 102e1, rotary magnet D3, battery, earth. When the *e*-wiper of the switch AW leaves contact 40, the circuit for relay V2 is cut off over winding II. This relay, however, remains energized over winding I parallel to the rotary magnet D3 while the operator transmits impulses. Relay V2 relapses at the end of the impulse series and by opening contact 97v2 causes the release of relay E1. Before relay E1 restores its contacts to normal however, a circuit for relay C1 is closed after relay V2 has released as follows: earth, contacts 113e1, 114v2, windings II and I of relay C1, wiper c set to the required subscriber's T-72c1, a-wiper of the switch AW set to the required subscriber to be guarded in known manner. The exchange line is switched through at contacts 72c1 and 73c1 and the required subscriber is rung from the ringing current source of supply over: contact 115h, winding I of relay S, contact 75 72c1, *a*-wiper of the switch AW set to the required subscriber, back over the called subscriber's station, *b*-wiper of the switch AW, contact 73c1, winding II of relay S, earth. When the called subscriber answers, relay S is energized in a ringing pause in known manner and at contact 89s cuts off the circuit for relay H so that the ringing current is cut off due to the opening of contact 115h. The operator, by means of her speaking set is connected to the called subscriber over contacts 116R and 117R and can now inform him that he is required for an exchange call. She then throws over the keys A and R and the calling exchange subscriber is then in direct communication with the required substation subscriber.

When the conversation is ended and the substation subscriber replaces his receiver, relay S releases. By opening its contact 77s and closing 79s relay S causes relay B1 to be short-circuited. Relay B1 restores its contacts to normal after its winding I has been short circuited and by contacts 82v1, 83b1 and 84s also restores relay C1. The release of relay C1 de-energizes relay V1 due to the opening of contact 81c1. Winding II of the driving magnet WR1 is energized over contact 68c1 in the following circuit: earth, relay interrupter RU1, contact 68c1, *d*-wiper of the stepping switch WR1 in position 1—10, contact 118R, winding II of the driving magnet WR1, battery, earth. The stepping switch WR1 continues to operate until it reaches its normal position. When this occurs, the rotary magnet D3 receives impulses over: earth, relay interrupter RU1, contact 68c1, *d*-wiper of the stepping switch WR1 in zero position, contact 119w3, rotary magnet D3, battery, earth. The rotary magnet D3 operates continually until the *e*-wiper of the switch AW reaches its zero position and in this position has caused a differential winding of relay W3 to be connected up over: earth, battery, resistance W4, *e*-wiper of the switch AW in position 0, contact 120w3, winding II of relay W3, earth, whereupon relay W3 restores its contacts to normal. The release of relays C1 and B1 causes the circuit for relay V1 to be cut off and all the switching means in the system are then restored to their original positions.

What I claim as new and desire to secure by Letters Patent is:

1. Circuit arrangement for automatic telephone systems provided with a plurality of parallel connected switches or sets of switch wipers characterized in that when a switch or set of switch wipers to be operated is identified a relay is energized which then causes the switching-over required for the setting of the switch or set of switch wipers to be carried out and is maintained energized independent of the setting of the switch until said switch is restored to normal.
2. In an automatic telephone system a movable switch wiper, means for moving said wiper, a relay, a circuit for said relay closed by the wiper when it leaves its normal position, and means for maintaining said relay energized independent of said switch wiper until the switch wiper is restored to normal.
3. In an automatic telephone system a movable switch wiper, means for moving said wiper, a relay, a circuit for said relay closed by the wiper when it leaves its normal position, said relay having a differential winding, and a circuit for energizing said winding when the switch returns to normal to release said relay.

4. In an automatic telephone system a plurality of sets of wipers connected in parallel, means for operating said wipers, means for selecting a set of said wipers for use, a relay energized when the selection is completed, means controlled by said relay for controlling the operating means of the wipers, said relay maintained energized independent of the setting of the switch wipers until the said wipers are returned to normal.
5. In an automatic telephone system, an automatic switch, means for operating said switch to automatically select calling lines and in another instance to operate the switch directly to seize a called line, a marking device in the switch, and means for operating said device to mark the desired group of lines to be selected in either type of connection before such selection is performed.
6. In an automatic telephone system, a trunk line, an automatic switch, lines accessible to said switch, means for operating said switch in response to a call over said line to extend a connection therefrom over the trunk, means for operating said switch in response to a call over said trunk to operate the switch as a final selector to seize a called one of said lines, and a marking switch operated in each type of connection to mark the group of lines to be selected before such selection is performed.
7. In an automatic telephone system, a combined line finder and connector switch having an operating magnet operated when the switch is used as both a connector and a finder switch to select a calling or a called line, and an auxiliary marking device for determining the group of contacts to be selected.

FRANZ SIMON.
